TOY AIRPLANE

Hans J. Meffert, Michelet 43-7,
Mexico City 5, Mexico

Filed Jan. 3, 1974, Ser. No. 430,468

Term of patent 14 years

Int. Cl. D21—01

U.S. Cl. D34—15 HH

FIG. 1

FIG. 2

FIG. 3

FIG. 4

FIG. 5

FIG. 1 is a top plan view of a toy airplane showing my new design;

FIG. 2 is a rear elevational view thereof;

FIG. 3 is a bottom plan view thereof;

FIG. 4 is a front elevational view thereof; and

FIG. 5 is a side elevational view thereof.

I claim:

The ornamental design for a toy airplane, substantially as shown and described.
